UNITED STATES PATENT OFFICE.

MIKOLAJ TARAS, OF TOLEDO, OHIO, ASSIGNOR OF ONE-HALF TO JOHN BARTUZEL, OF YOUNGSTOWN, OHIO.

RAIL-JOINT.

1,228,716.

Specification of Letters Patent.

Patented June 5, 1917.

Application filed October 19, 1916. Serial No. 126,506.

To all whom it may concern:

Be it known that I, MIKOLAJ TARAS, a subject of the Emperor of Austria, and a resident of Toledo, in the county of Lucas and State of Ohio, have invented certain new and useful Improvements in Rail-Joints, of which the following is a specification.

This invention relates to improvements in rail fastening devices, as applied to standard railway construction, and has as its principal object the provision of means whereby the saddle, upon which the ends of the rails are engaged, is so arranged as to positively engage and clamp the abutting ends of the rails.

A further object is to provide such fasteners in forms which may be readily applied or removed, the fasteners being relatively inexpensive to construct and applicable to present existing conditions.

These and like objects are attained by the novel construction and combination of parts hereafter described and shown in the accompanying drawings forming a part of this specification, and in which:

Figure 1 is a perspective view showing a fragment of track and indicating the application of the fasteners.

Fig. 2 is an enlarged plan view showing one of the fasteners as applied.

Fig. 3 is a transverse sectional view taken on line 3—3 of Fig. 2, and

Fig. 4 is a like transverse sectional view taken on line 4—4 of Fig. 2.

Throughout the several views, the numeral 10 indicates the ties or sleepers, of usual construction as are also the rails 12, the latter being provided with the usual openings to receive the through-bolts by means of which the fish or joint plates are engaged with the sides of the rail stem 14.

The base 15 of the rail normally rests upon the upper surface of the ties, to which it is secured by means of spikes 16. In order to hold the abutting ends firmly in position so that the rails are in accurate alignment, both laterally and vertically, a saddle 18 is provided, formed to suit the base 15 of the rail, one side 19 being raised vertically and joined by an angular bent portion 20 to a vertical element 21 which constitutes one of

the splice bars or fish plates, the same being preferably disposed upon the inner side of the rail, that is to say, upon the side adjacent to the opposite rail. On the outer or opposite side of the base plate 18 is an inwardly curved ledge 23 having cuts 24 contiguous to its lateral edges so that the material 25 at the sides of the plate 18 can be bent downwardly, the remaining portion 28 being raised above the end portions.

An oppositely disposed joint plate 30 is suited to the other side of the rail and provided with an angularly disposed flanged element 31 adapted to be received in the space between the curved flange element 23 and upper surface of a rail base 15, the plate being prevented from longitudinal motion by reason of the downturned elements 25.

In the construction of these parts, the element 23 is preferably so formed as to have a resilient or spring-like effect whereby it exerts a tension or grip upon the flange 31, holding it firmly in position, pressed against the flanged base of the rail.

Bolts 35 are inserted through openings formed in the fish plates, the same passing through openings in the web or stem 14 of the rail, the bolts being provided with nuts 36 by means of which the fish plates are drawn tightly against the rail.

In addition to the holding means described, lag screws 38 are used, one being inserted on each side of the rail joint passing through the flange 31 of the joint plate while upon the opposite side of the rail, ordinary railway track spikes are used to hold the structure to the ties.

From the foregoing, it will be seen that a simple, cheaply constructed and effective rail joint fastening is indicated.

Having thus described my invention, what I claim as new, and desire to secure by Letters Patent, is:

In a rail joint, a splice bar comprising a vertical side portion provided at its lower edge with an outturned flange adapted to overlie the base of a rail, a base plate formed integrally with the outer edge of said flange, adapted to underlie the rail, a raised resilient element formed on the opposite side of said base plate, a second spike bar

lesser length having a vertical portion engageable with the stem of the rail and a flange portion adapted to overlie the base of the rail, said flanged portion being ⁵ engageable below said resilient portion of the first named splice bar, means formed with said first mentioned splice bar preventing

longitudinal motion of the second splice bar, and means for securing both of said splice bars to the rails and tie therebelow.

16

Signed at Toledo, in the county of Lucas, and State of Ohio, this 25 day of September, 1916.

MIKOLAJ TARAS.
